UNITED STATES PATENT OFFICE.

LAWRENCE E. GRABAU, OF BONAIR, IOWA.

SNOW-PLOW.

1,274,708.

Specification of Letters Patent.

Patented Aug. 6, 1918.

Application filed April 1, 1918. Serial No. 226,004.

To all whom it may concern:

Be it known that I, LAWRENCE E. GRABAU, a citizen of the United States, residing at Bonair, in the county of Howard and State of Iowa, have invented certain new and useful Improvements in Snow-Plows, of which the following is a specification, reference being had to the accompanying drawings.

This invention relates to snow plows and 10 has for its primary object to provide a snow plow of the rotary type which is applicable to the ordinary motor driven truck, for the purpose of removing snow and ice from roads or highways.

15 It is another and more particular object of my invention to provide improved means whereby the plow will cut its way with ease and facility through heavy snow banks or drifts and without liability of injury 20 thereto.

It is also an important object of the invention to provide an improved mounting and arrangement of the rotary plows, a pair of such plows being employed each operating 25 within a casing partially open on its front side, and means for delivering the snow and ice within the respective casings to said plows.

It is still another object of the invention 30 to provide adjustable means for effectively loosening packed snow or ice close to the road surface.

And it is a further general object of my invention to provide a snow plow as above 35 characterized which is relatively simple in its construction, may be manufactured at a small cost, and can be easily applied to or removed from the ordinary motor driven truck.

40 With the above and other objects in view, the invention consists in the improved combination, construction and relative arrangement of the several parts as will be herein-after more fully described, subsequently 45 claimed and illustrated in the accompanying drawings wherein similar reference characters designate corresponding parts throughout the several views, and in which:

Figure 1 is a side elevation of a snow 50 plow constructed in accordance with the preferred embodiment of my invention;

Fig. 2 is a top plan view, a portion of one of the plow casings being broken away;

Fig. 3 is a front end elevation;

55 Fig. 4 is a section through one plow taken on the line 4-4 of Fig. 3;

Fig. 5 is a section taken on the line 5-5 of Fig. 1;

Fig. 6 is a detail perspective view of one of the plow fans; and

Fig. 7 is a rear end elevation showing the plow gearing in inoperative position.

Referring in detail to the drawings, 5 designates the chassis or frame of a motor vehicle truck, which is provided at its forward end with the usual engine for the propulsion of the vehicle and the customary steering mechanism.

Fixed to the forward end of the frame 5 and extending beyond the opposite sides of 70 said frame a transverse beam 6 is suitably secured. A pair of plow casings or housings 7 are mounted upon the front side of this beam and are provided with tangentially disposed rearwardly opening outlet necks or 75 extensions 8 which project beyond the opposite sides of the machine. Each of the casings 7 at the lower side thereof has an opening 9 in its front wall, and to the annular body walls of these casings at the lower side 80 thereof and in line with the longitudinal center of the machine, a forwardly projecting wedge-shaped spur 10 is secured.

In suitable bearings 11 on the beam 6 the shafts 12 are rotatably mounted, said shafts 85 extending through the respective casings 7 at their axial centers. Within each casing 7, a rotary plow 13 is fixed upon the shafts 12. Each of these plows consists of a plurality of radially extending transversely 90 curved blades 14, and these blades at their rear edges are securely fixed or integrally formed with a circular disk or plate 15, the perimeter of which is coincident with the outer end edges of the plow blades. These 95 disks serve a very useful purpose in the operation of the plow. First they reinforce and strengthen the blades of the plow, preventing their relative distortion from normal position, secondly, they prevent the 100 leakage of air and snow between the rear edges of the blades and the rear walls of the casings 7, thereby also reducing friction which would otherwise result by the snow coming in contact with the housing wall, 105 third, to prevent sticking or clogging of the snow and fully utilize the centrifugal force of the rotating propeller, and fourth, to increase the capacity of the individual plows when operated under a predetermined driving power.

To the extreme forward ends of the shafts

12 which project some distance in advance of the plow casings 7, the snow breaking or cutting propellers 16 are fixed, said advance propellers having relatively short 5 blades, any desired number of which may be provided. Rearwardly of these front propellers, a second set of propeller blades 17 is fixed upon each shaft 12, the latter propeller blades being of appreciably 10 greater length, and substantially equal to the length of the plow blades 14. The blades 17 are disposed intermediate of, or in staggered relation to, the front blades 16. It will thus be seen that in the forward movement of the machine, the advance cutting or breaking propellers 16 first enter the snow and break up or loosen the same, and then the longer blades 17 operate to direct the loosened snow rearwardly and through 15 the openings 9 in the front walls of the casings 7 into said casings and against the disks 15 of the respective plows. In the rotation of these plows in relatively opposite directions, the blades thereof discharge the snow with considerable force through the tangentially extending outlet necks 8 on the casings, from which the snow is directed to the opposite sides of the road or highway and out of the line of traffic. 20

20 The mass of snow which is forced rearwardly by the blades 17 is supported and directed through the openings 9 of the plow casings by means of a supporting and directing plate or scoop 18 which extends transversely at the lower sides of the casings and in advance thereof and is pivotally mounted as at 20 upon the forward ends of the longitudinally extending supporting bars 19 which are suitably attached or secured at 25

25 their rear ends to the front axle of the vehicle. These supporting bars are braced by means of the inclined hangers 21 depending from the beam 6, the lower ends of said hangers being secured to the forward ends of the supporting bars. The directing plate 18 at its forward edge is toothed as shown at 22 so as to cut into and break up packed snow or ice adjacent the surface of the road bed. Inwardly and rearwardly inclined 30

30 baffle plates 23 are fixed to the upper surface of the plate 18 adjacent each end thereof and serve to deflect the snow inwardly through the openings of the plow casings. The forwardly projecting wedge-shaped spur 10 located at the center of the plate 18 and between the open sides of the casings 7, effects a division of the snow as it is forced rearwardly from the plate 18 by the propellers 17, so that the snow is delivered 35 substantially in uniform quantity into the respective plow casings.

I have also provided means for adjusting the plate 18 so as to dispose its forward toothed edge 22 as close to the road surface 40 as may be practicable. To this end, a rock

shaft 24 is mounted at the rear side of the beam 6 in bearings 25 and is provided upon each of its ends with a forwardly extending arm 26. Rods 27 connect the respective arms 26 to the relatively opposite ends of the plate 18. The shaft 24 is actuated by means of a lever 28 mounted upon the vehicle frame convenient to the driver's seat and having the usual locking dog for engagement with the teeth of a rack or quadrant 29. A forwardly extending rod 30 is connected to the lever 28, the forward end of said rod being pivotally connected to an upstanding arm 31 fixed upon the shaft 24. In order to limit the downward swinging movement of the plate 18 so that its forward edge may not be disposed too close to the road surface, I provide the rods 32 which are pivotally connected at their forward ends to vertically disposed cutter blades 33 fixed upon the plate 18 at its opposite ends outwardly of the baffle plates 23. The rods 32 at their rear ends extend through slots 35 in the bracket plates 34 which are fixed to the beam 6. These rear ends of the rods 36 are threaded to receive the adjustable nuts 36. These nuts act as stops, and it will be readily seen that by adjusting said nuts, the downward swinging movement of the plate 18 can be properly limited. The vertical cutter blades 33 cut into the snow and ice at the opposite sides of the machine and together with the baffle plates 23 direct the same inwardly to the propeller 17 and into the plow casings 7. Preferably, I provide 45 separate means other than the vehicle motor for driving the rotary plows. This driving means I will now proceed to describe in detail.

Upon the rear end of the machine frame or chassis, an engine indicated at 37 and which may be of any preferred type is suitably mounted. This engine is operatively connected to a crank shaft 38 upon each end of which a fly wheel 39 is fixed. Each of the 50 fly wheels is provided upon its outer face with a beveled or mitered friction wheel 40. The plow shafts 12 at their rear ends are mounted in bearings 41 fixed upon the upper ends of the yieldable standards or supports 42. The shafts 12 in spaced relation to the standards 42 are each provided with a universal joint indicated at 12'. These standards are fixed at their lower ends to the longitudinal side bars of the vehicle frame 55 and are preferably in the form of heavy spring metal bars capable of a transverse yielding movement. To the shaft bearings 41 on the upper ends of said standards, rods 43 are pivotally connected at their outer 60 ends. A lever 44 is fulcrumed as at 45 adjacent to one of its ends and to this lever at opposite sides of its fulcrum, the inner ends of the rods 43 are respectively pivoted as shown at 46. The lever 44 carries a lug or 65

dog for locking engagement with the teeth of a quadrant 47. To the rear end of each plow shaft 12 a friction pinion 48 is fixed having operative engagement with one of the friction wheels 40. From reference to Fig. 2 of the drawings, it will be readily seen that when it is desired for any reason to suspend the operation of the plows, the lever 44 is shifted in the proper direction to force the rods 43 outwardly, thereby urging the upper ends of the yieldable standards 42 outwardly and disengaging the friction pinion 48 from the friction wheels 40. While I have specifically described a particular means for transmitting power from the engine 37 to the rotary plows, it will of course be readily appreciated that various other means might be devised for this purpose.

From the foregoing description taken in connection with the accompanying drawing, the construction, manner of operation and several advantages of my improved motor snow plow will be fully understood.

The rotary plows and the associated parts can be readily applied to the ordinary motor vehicle truck without necessitating any material structural alterations therein. By means of my improved plow attachment, heavy banks of snow which would ordinarily close the road to traffic, may be removed and disposed of in a very expeditious manner. By the provision of the adjustable plate 18, hard packed snow or ice may be broken up close to the road surface and removed. By providing the advance sets of cutting or breaking propellers and constructing and arranging the rotary plows within the housings or casings in the manner above explained, the possibility of the breakage of the blades or other parts of the mechanism when extraordinary heavy duty devolves thereon, is reduced to a minimum. At the same time, it is to be noted that the various parts of the device are of relatively simple form so that the invention as a whole may be produced at comparatively small manufacturing cost.

While I have herein shown and described the preferred form, construction and relative arrangement of the various elements, it is to be understood that the device is susceptible of many modifications therein, and I therefore reserve the privilege of adopting all such legitimate changes as may be fairly embodied within the spirit and scope of the invention as claimed.

Having thus described my invention, what I claim is:

1. The combination with a motor vehicle, of a plow casing and means for mounting the same upon the forward end of the vehicle frame, said casing having an opening in its front wall, a rotary plow mounted in said casing, a snow supporting and direct-

ing plate pivoted at the lower edge of the plow casing for vertical swinging movement, means for adjusting said plate to vary the inclination thereof, rods to support the plate and limit its downward swinging 70 movement, guides for said rods on the vehicle frame, and stop members adjustable on the rods to coact with the guides and dispose the forward edge of the plate at a predetermined elevation above the road surface. 75

2. The combination with a motor vehicle, of a plow casing and means for mounting the same upon the forward end of the vehicle frame, said casing having an opening 80 in its front wall, a rotary plow mounted in said casing, a snow supporting and directing plate pivoted at the lower edge of the plow casing for vertical swinging movement, means for adjusting said plate to vary 85 the inclination thereof, obliquely inclined baffle members fixed upon the upper surface of said plate, vertical cutter blades on the plate, rods pivoted at one of their ends to said cutter blades, guides for said rods on 90 the vehicle frame, and adjustable stops on the rods to coact with said guides and position the forward edge of the plate at a predetermined elevation above the road surface. 95

3. The combination with a motor vehicle, of a pair of plow casings and means for mounting the same upon the forward end of the motor vehicle frame, a rotary plow mounted in each of said casings, each casing 100 having an opening in its front wall, a transversely disposed plate extending forwardly from the lower edges of the plow casings, obliquely inclined baffle plates fixed upon said transverse plate at the opposite 105 ends thereof to direct the snow inwardly through the openings in the respective casings, and a central forwardly projecting spur fixed to the casing walls to direct the snow into the respective casings. 110

4. The combination with a motor vehicle, of a pair of plow casings and means for mounting the same upon the forward end of the motor vehicle frame, a rotary plow mounted in each of said casings, each casing 115 having an opening in its front wall, a transversely disposed plate extending forwardly from the lower edges of the plow casings, obliquely inclined baffle plates fixed upon said transverse plate at the opposite ends 120 thereof to direct the snow inwardly through the openings in the respective casings, a central forwardly projecting spur fixed to the casing walls to direct the snow into the respective casings, and vertically disposed cutters fixed upon said transverse plate outwardly of the respective baffle plates. 125

5. The combination with a motor vehicle, of rotary snow plows and means for mounting said plows upon the forward end of the 130

vehicle frame, each plow having a rearwardly extending shaft, yieldable supporting standards for the rear ends of said shafts, an engine mounted upon the rear end of the vehicle frame, means for transmitting rotation from the engine to said plow shafts including driving elements and driven elements fixed to the rear ends of the plow shafts, and manually operable means connected to said supporting standards to

urge the same from their normal positions and disengage the driven elements from the driving elements.

In testimony whereof I hereunto affix my signature in the presence of two witnesses. 15

LAWRENCE E. GRABAU.
